Alan T. Johnson
ATTORNEY

UNITED STATES PATENT OFFICE.

SAMUEL FRIEDMAN, OF NEW YORK, N. Y.

SNOW-REMOVING APPARATUS.

1,242,433.

Specification of Letters Patent.

Patented Oct. 9, 1917.

Continuation in part of application Serial No. 86,780, filed March 25, 1916. This application filed June 14, 1916. Serial No. 103,642.

To all whom it may concern:

Be it known that I, SAMUEL FRIEDMAN, a citizen of the United States, and a resident of New York, in the county of New York and State of New York, have invented certain new and useful Improvements in Snow-Removing Apparatus, of which the following is a specification.

This application is a continuation in part 10 of my co-pending application filed March 25, 1916, Serial No. 86,780 for "snow removing apparatus and method."

It is well known that in cities the removal 15 of snow from the streets is a very expensive and laborious operation. The ordinary practice is for shovelers to manually place this snow in carts and the snow is hauled away, often long distances before a suitable dumping ground can be found.

20 My improved apparatus and method is to simplify the removal of the snow, and in the preferred form of my invention, the removal of the snow is almost a continuous operation, there being no necessity of carrying 25 the load any appreciable distance, but on the contrary it is carried along the street to the next sewer manhole into which it is dumped, having first been preferably in my preferred form, converted into a liquid or semi-liquid 30 mass, such as slush by suitable means and treatment.

Should the distance between the manholes be comparatively short, the operation of my apparatus and method will be substantially 35 continuous. Should the manholes be at a great distance then it is only necessary for my preferred apparatus after it is loaded, to be drawn a block or some such distance to the nearest manhole where it can be dumped, 40 and then immediately continue its snow removing operation. For example, if there be a manhole at each end of a block, my improved apparatus may obtain one load traveling to one manhole, and another load traveling 45 back to the first manhole, so that there would be no time lost and the expense of carrying the load to a distant dumping ground would be avoided. In this preferred form of my apparatus I treat the 50 snow and ice which is scraped up from the street, by some chemical means which would change it into a liquid or semi-liquid such as

slush. Preferably the snow and ice while being so treated, are agitated in a suitable manner, so as to insure quick action of the 55 chemical. I may also, although not necessarily, employ waste heat to further insure the snow and ice being brought into a liquid or semi-liquid state. The means which I preferably employ are the exhaust 60 gases coming from the automobile or truck which is preferably used to draw my improved apparatus. When this form is used, a connection may be made around the muffler so that the exhaust gases may be permitted to pass directly into the snow and ice 65 temporarily carried in the apparatus. The snow and ice will have the effect on these exhaust gases passing up through them of a muffler and at the same time the waste heat 70 will be used to convert the mass into a liquid or a slush, either with or without the use of the chemical, and either with or without agitating the mass by mechanical means.

In another form of my invention I omit 75 the snow and ice reservoir and use in place of that element a conveyer which may be raised or lowered to pass the snow and ice taken up from the street to wagons or carts which may travel on the side of my apparatus to receive it.

80 My invention further relates to certain details and combination of elements and methods which will more fully hereinafter be described in the specification and set 85 forth in the claims.

In the accompanying drawings showing 90 illustrative embodiments of my invention and in which the same reference numerals refer to similar parts in the several figures of the drawings:

Figure 1 is a longitudinal vertical section through my preferred apparatus, the tractor for pulling my apparatus being omitted;

Fig. 2 is a transverse vertical section on 95 the line 2—2 of Fig. 1;

Fig. 3 is a fragmentary side elevation partly in section of a modification showing an adjustable endless conveyer to pass the snow and ice to some vehicle which will 100 move with my apparatus; when it is loaded, a new one will take its place;

Fig. 4 is a transverse vertical section substantially on the line 4—4 of Fig. 3;

Fig. 5 is an enlarged vertical section showing more clearly the operation of the plow;

Fig. 6 is a vertical section showing the spring controlling the lower end of the 5 movable plow;

Fig. 7 is a fragmentary detail view showing the operation of the shovel; and

Fig. 8 is a detail view of a modified form of the plow.

10 Fig. 9 is a sectional detail illustrating the manner in which the shovels cut through the snow as they swing from the curved path of their travel into conveying relation to the inclined chute.

15 In the illustrative embodiments of my invention, 1 is the preferred form of my apparatus having a frame 2 mounted on the wheels 3 having an inclined chute 4, tank 5, endless conveyer 6 having shovels 7 which 20 are preferably curved as shown, the particular ends to be attained by the shovel curvature being set forth more fully in connection with the description of the preferred form of the invention shown in Fig. 7.

25 The endless conveyer 6 is mounted on the sprocket wheels 8, 8 and 9, 9 and with its shovels 7 preferably extends a little beyond the end 10 of the inclined chute 4. Power is transmitted to the endless conveyer 6 and 30 the curved shovels 7 in any suitable manner, such as by having the sprockets 9, 9 keyed upon the shaft 11 upon which is loosely mounted a supplemental sprocket 12, which is connected to the sprocket 13 carried by 35 the traction wheel 3, by the chain drive 14. By operating the handle 15 of the clutch 16 the sprockets 9, 9 are thrown into and out of engagement with the drive sprocket 12 in a well understood manner. This will of 40 course permit the drive sprocket 12 to run idly, without operating the endless conveyer 6 with its shovels while my apparatus is being drawn to the particular location where it is desired to remove the snow.

45 To the forward end of the inclined chute 4, I pivotally mount a plow 17. This plow, Figs. 1 and 2, is formed of a plurality of 50 movable elements which may move with relation to each other. I have shown the main portion of the plow as 18 and the supplemental portion being 19. Ordinarily these two portions 18 and 19 of the plow 17 are 55 adjusted to form one continuous and unbroken surface up which the snow and ice is forced onto the inclined chute 4, where it is cut by the inclined shovels 7 which are 60 preferably shaped, as shown in Fig. 7, so that the lower edge of each shovel strikes the snow nearly normal to the path of travel of 65 the snow up the chute as the shovel swings from its curved path of travel into conveying position, the snow being cut by the edge of the shovel and propelled by said shovel until it falls into the tank 5. It will be 70 noted that the curvature of the outer part of

each shovel is so related to the curvature of the curved part of the path of travel of said shovel that the shovel cuts edgewise through the snow as the shovel swings from its curved path of travel into conveying relation to the inclined chute 4, the particular curvature of the shovel preventing the packing of snow in front of the shovel, in such manner as to prevent the edge of the shovel from cutting through the snow, and also being such that it prevents the shovel from riding up in the snow, due to the action of the snow behind the shovel as it is cutting through the snow.

75 In case, however, that the plow picks up more snow and ice than the conveyer 6 and the curved shovels 7 can comfortably move without straining the parts, or in other words, such snow and ice become momentarily jammed or wedged approximately at the point 20, the operator can move the lever 21 so as to pull up on the connecting rod 22 and cause the auxiliary member 19 to move down as substantially shown in dotted lines in Fig. 1, which will permit the surplus snow and ice to drop by gravity, (which action may be supplemented by the operator) back upon the street, and thereby relieve the apparatus from this excess. Then the lever 21 is moved back into the position so that the 85 part 19 will form one continuous unbroken surface with the part 18 as shown in full lines in Figs. 1 and 2.

90 The main portion 18 of the plow may be raised and lowered to regulate the amount of snow and ice to be forced onto the inclined chute 4 by manipulating the lever 23 which operates the rod 24 to raise or lower the plow 18 in a vertical direction. This is also taken advantage of to compensate for 95 the irregularity or roughness of the roadway. Over asphalt for example, the point 25 of the plow 18 can be brought very close to the roadway. Over rough surfaces, however, such as cobblestones or any other rough 100 surface, it is raised as shown for example in Fig. 1.

105 To permit my device to be used either on a smooth or rough surface I use a guard plow 26, which is drawn out of the way 110 by operating the lever 27, when the apparatus is passing over asphalt or other smooth surface. When it passes over a rough roadway, as cobblestones or any other rough 115 surface, the parts are brought into position 120 as shown in Fig. 1, when the guard plow 26 is brought beneath the point 25 of the main plow 18.

125 This guard plow 26 is mounted on a shaft 28 carried by the rod 29. When the guard plow strikes an obstruction, as for example, the stone 30, Fig. 5, the guard plow 26 rotates upon the pin 28 against the action of the spring 31, Fig. 6, permitting the plow to pass harmlessly over the obstruc- 130

tion 30 without injuring the apparatus. The moment it is past the spring 31 rotates the guard plow back into its operative position such as is shown in Figs. 1 and 5, and is 5 checked by a stop from being drawn further forward than normal position.

I preferably also employ a gage 32 movable vertically in any suitable manner by sliding in the guides 33, 33. I have shown 10 a hand wheel 34 operating the screw 35 to accomplish this adjustment through the member 36 which is secured to the gage 32. This gage limits the amount of snow and ice which shall be forced up the inclined 15 chute 4. It is directed obliquely to the curved shovels 7 and the inclined chute 4 so that the undesired quantity of snow is forced to one side of the machine. The forward end 37 of my apparatus is secured 20 to the portion 38 of a tractor by any suitable means such as a pin 39.

I may form my plow 118 with a supplemental pivoted member 119 which is kept in proper position by means of a spring 120 all shown diagrammatically in Fig. 8, a finger 121 limiting the throw of the spring 120. In this form the supplemental member 119 will automatically swing downwardly against the action of spring 120 the 30 moment that the device is overloaded and will swing back again as soon as the excess has been dumped.

The curved shovels 7 have stay rods 40 which are also connected to the chain 6, the 35 curve of the shovels and their inclination to the conveyer being such, as shown in Fig. 7, that they positively pierce or cut the snow and ice as it is fed up the inclined chute 4. It passes up this incline before it 40 drops into the tank 5 where it is preferably treated by some chemical solution which will convert it into a liquid or slush. This may be done by various means. I have shown in my apparatus a reservoir 41 which 45 is preferably divided into two parts by a plate 42, a spigot 43, a valve 44 controlling the flow of the chemical solution 45 from the upper compartment of the reservoir to the lower one. In the upper portion of the 50 reservoir I place a series of containers 46, 46 each having an opening 47 covered by a slide 48. By pulling out the slide 48 the contents of the first receptacle 46 may be dropped into the upper portion of the reservoir and then passes through the spigot 43 55 into the lower portion 49 and thence through a perforated plate 50 and the opening 51 onto the snow and ice in the tank 5. As additional chemical is needed the plate 48 60 may be pulled out releasing the second container 46 and so on.

The chemical which I preferably use is ordinary salt, though this may of course be varied. I may use sodium chlorid or calcium chlorid, or both, preferably the salt so-

lution is not less than one per cent., though of course this may be varied.

Preferably I use enough salt solution to convert the snow into a non-ball ing slush and preferably one which will readily flow. 70 This also applies to any other chemical solution which may be employed to act on the snow and ice.

The opening 51 is preferably so located as to project a stream of salt solution on the 75 snow and ice just as it is about to fall into the tank 5. This insures that every portion of the snow and ice will receive some of the salt solution before it is mingled or mixed with the snow and ice which preceded it 80 into the tank 5.

While the snow and ice are in the tank 5 they may be mechanically agitated, as for example, by the agitator 52 operated by the chain 53 passing over the sprocket 54 carried by the traction wheel 3, the agitator comprising blades carried by a horizontal shaft 54' parallel to the inclined bottom of the tank and supporting the blades clear of said bottom so that they do not interfere 90 with the discharge of the slush from the tank. When it is desired to dump the load the lever 55 is operated permitting the door 56 to swing outward so that the entire load may be dumped as for example, in the sewer 95 manhole.

In connection with the chemical treatment of the contents in the tank 5 or separate from the chemical treatment, I may permit the waste gases from the tractor (not shown) to pass from the engine through the pipe 57 directly into the slush in the tank 5. This connection 57 may be made either to take the gases from the muffler, or may take them directly from the engine 100 without passing through the muffler letting the contents of the tank act as a muffler and at the same time absorb the waste heat. When the spent gases have passed in through the tank 5, they may pass out of 105 the apparatus through the opening 58.

In my modified structure shown in Figs. 3 and 4, the endless conveyer 6 operates the gears 59, 60, 61 and 62, which latter is mounted on an axle 63 on which is mounted 110 a pulley 64 over which passes an endless belt 65 mounted in an adjustable cradle 66 which is raised and lowered in any suitable manner as by means of a chain 67 passing over the sheave 68.

In the form shown in Figs. 3 and 4 the snow and ice are brought up by the conveyer 6 and are dumped onto the second endless conveyer 65, which may be raised or lowered dependent upon the height of the 120 wagon which travels on the side of my apparatus to receive such loads. In this form the snow and ice will not pass into a tank nor are they treated preparatory to dumping. The conveyer need not neces- 130

sarily be raised and lowered. The cradle is provided with a tooth or portion 69 to scrape off the snow from the conveyer 65.

I have described my invention in connection with several illustrative embodiments of my apparatus, but to the details of which I do not desire to be limited. What is claimed as new and what it is desired to secure by Letters Patent is set forth in the appended claims.

1. In a snow removing apparatus the combination of an inclined chute, an adjustable plow mounted at the end of the chute, means for securing said plow in different adjusted positions with respect to said chute and a guard plow mounted in advance of the main plow.

2. In a snow removing apparatus the combination of an inclined chute, an adjustable plow mounted at the end of the chute, and an adjustable yielding guard plow mounted in advance of the main adjustable plow, and means for securing said plows in different positions of adjustment.

3. In snow removing apparatus, the combination with snow gathering means, of an adjustable depth gage presenting a snow engaging face inclined to deflect from the field of operation of the snow gathering means snow in excess of a selected depth.

4. In a snow removing apparatus the combination of an inclined chute, and an adjustable plow mounted at the end of the inclined chute and an adjustable gage to limit the amount of snow and ice to be fed to the inclined chute, means for securing said adjustable parts in different positions of adjustment and a guard plow in front of said adjustable plow.

5. Snow removing apparatus comprising, in combination, a plow for gathering up the snow from the street, means for conveying away the snow gathered up by said plow, a guard plow adjustable into and out of operative relation to said plow, and means for securing said guard plow in either of said relations to said main plow.

6. Snow removing apparatus comprising, in combination, a main plow for gathering up the snow from the street, means for conveying away the snow gathered up by said plow, and a narrow horizontally pivoted guard plow in front of said main plow, said guard plow being arranged to swing about its horizontal axis to pass an obstruction without disturbing the position of said main plow.

7. In snow removing apparatus, a vertically adjustable main plow for picking up the snow, an independently adjustable guard plow in front of said main plow, and a snow depth gage also located in front of said main plow.

8. In snow removing apparatus, a main plow for picking up the snow, a guard plow

in front of said main plow, and means for moving said guard plow into and out of operative relation to said main plow.

9. In snow removing apparatus, a main plow for picking up the snow, a guard plow in front of said main plow, and means for effecting independent adjustments of said plows.

10. In snow removing apparatus, a plow for picking up the snow, said plow being adjustable about a horizontal axis to bring it to different elevations from the street, and a trap in said plow arranged to turn about the same axis.

11. In snow removing apparatus, an inclined chute, a main plow pivoted at the lower end of said chute to swing about a horizontal axis into different positions of adjustment with respect to the surface to be cleaned, means for effecting such adjustment and securing the plow in adjusted position, and an independently adjustable horizontally pivoted guard plow in front of said main plow.

12. In snow removing apparatus, the combination with snow gathering means, of means for conveying away from the gathering means the snow gathered thereby, and means located substantially at the point of coöperation of said gathering and conveying means constructed and arranged to be opened to discharge anything which tends to clog the operation of the apparatus.

13. In snow removing apparatus, a portable receptacle for the snow, a plow for picking up the snow, said plow being adjustable to bring its end into different elevations from the street, an adjustable snow gage in front of said plow, and means for securing said gage and plow in the different positions of adjustment.

14. In snow removing apparatus, the combination with snow gathering means, of means for conveying away from the gathering means the snow gathered thereby, and means normally coöoperating with the aforementioned means to direct the snow through the apparatus but arranged to be moved out of directing relation thereto to discharge from the apparatus anything tending to interfere with its operation.

15. In snow removing apparatus, a plow, a conveyer for the snow picked up by said plow, a gage in front of said plow for limiting the amount of snow operated upon by said plow, and means providing for the discharge from said apparatus of snow picked up by said plow in excess of that which can properly be handled by said conveyer.

16. In snow removing apparatus, a plow, a conveyer for the snow picked up by said plow, said plow having a movable part providing for the discharge from the apparatus of snow picked up in excess of that which can properly be handled by said conveyer.

17. In snow removing apparatus, the combination with an inclined chute, a plow at the lower end of said chute, an endless conveyer arranged to move snow picked up by said plow along said chute, and discharging means at the point where said conveyer engages the snow picked up by said plow, said means normally supporting the snow for the action of the conveyer but being movable to discharge from the apparatus snow picked up in excess of that which can readily be handled by said conveyer.

18. In snow removing apparatus, a plow for gathering up the snow from the street, means for conveying away the snow gathered up by said plow, and a downwardly opening trap in said plow for discharging anything which may tend to interfere with the operation of said apparatus.

19. In snow removing apparatus, a plow for gathering up the snow from the street, means for conveying away the snow gathered up by said plow, a trap in said plow for discharging anything which may tend to interfere with the operation of said apparatus, and means under the control of the operator for operating said trap.

20. Snow removing apparatus comprising, in combination, snow gathering means, means for conveying away from said gathering means the snow gathered thereby, and a vertically adjustable gage in front of said gathering means presenting a snow engaging face so inclined to the path of travel of the apparatus as to move to one side of the apparatus the excess snow, where the depth of the snow is greater than that for which the gage is set.

21. In snow removing apparatus, means for gathering up the snow from the street, means for conveying away the snow gathered by said gathering means, means for adjusting the height of said gathering means from the street and a gage in front of said gathering means for determining the vertical amount of the snow to be operated upon.

22. Snow removing apparatus comprising, in combination, a part presenting an inclined surface up which snow gathered by said apparatus is to be moved, and an endless conveyer for moving snow up said incline, said conveyer comprising an end-

less carrier and shovels inclined rearwardly from their edges nearest the carrier and so curved forward toward their outer edges that said edges effect an edgewise cut through the snow as said shovels swing from their curved path of travel into conveying relation to said incline, the curvature of the outer part of each shovel being so related to the curvature of the curved part of the path of travel of said shovel that the aforesaid cutting movement of the shovel is edgewise, but said shovel being not curved so far forward as to pocket the snow independently of its support upon the incline or that the rear face of the shovel during the cutting movement presents a deflecting surface so inclined to said movement as to tend to cause the shovel to ride up in the snow.

23. Snow removing apparatus comprising, in combination, a part presenting an inclined surface up which snow gathered by said apparatus is to be moved, and an endless conveyer for moving snow up said incline, said conveyer comprising an endless carrier, and shovels projecting outward from said carrier and so bent forward toward their outer edges that said edges cut edgewise through the snow as said shovels swing from their curved path of travel into conveying relation to said incline, but not bent so far forward as to pocket the snow independently of its support upon the incline, or that the rear face of each shovel presents a deflecting surface tending to cause the shovel to ride up in the snow as its edge is cutting through the snow.

24. In a snow removing apparatus, the combination with snow gathering means and a tank having an inclined bottom, and means for discharging the tank at the lower end of said incline, of means for conveying the snow picked up by said gathering means to said tank, means for spraying the snow with a melting solution, and means for agitating the mixture in the tank, said means comprising a horizontal shaft parallel to said bottom and spaced blades carried by said shaft clear of said bottom.
